United States Patent Office.

E. D. NORTON, OF CUBA, NEW YORK.

Letters Patent No. 96,470, dated November 2, 1869.

IMPROVED DOOR-SPRING.

The Schedule referred to in these Letters Patent and making part of the same.

To all whom it may concern:

Be it known that I, E. D. NORTON, of Cuba, in the county of Allegany, and in the State of New York, have invented a new and useful Improvement in Door or Gate-Springs; and I do hereby declare that the following is a full, clear, and exact description of the construction and operation of the same, reference being had to the annexed drawings, making a part of this specification, in which—

Figure 1 is a front elevation of door or gate with my improved spring attached.

Figure 2 is a top view of spring.

Figure 3 is a front view of same.

My invention consists of an improvement in the methods formerly employed for closing doors or gates, by means of springs; and

Its object is to obtain a more serviceable and reliable spring than the ones hitherto in use for that purpose, so that the spring can be easily detached, or adjusted, or reversed, so that it will hold the door, either open or shut, according to the way in which the spring is placed.

To enable others skilled in the art to make and use my invention, I will proceed to describe its construction and operation.

A represents door or gate.

B, the frame.

C represents a steel, or iron, or brass pin, secured firmly to door-frame by means of screws or bolts, the pin sitting out from the frame a sufficient distance to allow the spring to be taken off or put on at ease.

D represents a double or single spiral spring, made to fit loosely over the pin C.

F represents a spring, attached firmly to door or gate, by means of screws or bolts, allowing said spring to set out toward the upper end, which is attached to end of the spring D by means of a link, marked E.

The operation is as follows:

When the door or gate is opened, the spring D is drawn out by the connecting-link E, and, when allowed to close, is drawn to by the action of the double or single spiral spring, connected with the spring F by connecting-link E. The combination of the spring D, and spring F, and connecting-link E keeps the door or gate tightly closed, by reason of the outward tendency of the spring marked F. Remove the spring, and place it upon its standard with the back coil upon the inside, and the spring will now hold the door open, instead of shut.

I am aware that spiral springs are used for closing doors and gates.

I do not claim as new the spiral spring for closing doors or gates; but

I do claim as new, and desire to secure by Letters Patent—

The removable and reversible spring D, formed of coiled wire, placed upon the standard C, and connected to the spring F by the link E, all as and for the purpose set forth.

In testimony that I claim the foregoing, I have hereunto set my hand, this 29th day of July, 1869.

E. D. NORTON.
